UNITED STATES PATENT OFFICE.

ELSIE MAY BLANK, OF AURORA, ILLINOIS.

CHILD'S GARMENT.

1,365,653.

Specification of Letters Patent. Patented Jan. 18, 1921.

Application filed April 21, 1920. Serial No. 375,486.

To all whom it may concern:

Be it known that I, ELSIE M. BLANK, a citizen of the United States, and a resident of Aurora, in the county of Kane and State of Illinois, have invented certain new and useful Improvements in Children's Garments, of which the following is a specification, reference being had to the accompanying drawings.

10 This invention relates to garments especially intended for infants that are young enough to have to wear diapers. One of the leading objects of my improved garment has to do with providing a construction that 15 will afford as much protection as possible to an infant from drafts or cold air during the changing of its diaper and at the same time afford full and free access to the diaper by the nurse or other attendant so that the desired change of diapers can be quickly and 20 easily effected. A further object of the invention is to provide a construction of the foot members of the garment that is not only simple and inexpensively made but 25 which will provide seamless soles for the feet. These objects I accomplish as illustrated in the drawing and as hereinafter particularly described:

In the accompanying drawing,—

30 Figure 1 is a rear view of the improved garment;

Fig. 2 is a view similar to Fig. 1 but showing the body portion partly unbuttoned and the rear flap of the lower member unbuttoned from the body portion and turned down;

Fig. 3 is a side elevation of the garment in approximately the position it would appear upon an infant lying upon its back,— 40 the front flap of the lower member being turned down and the lower portion of the front of the body member being turned slightly upward so as to afford free access to the infant's diaper;

45 Fig. 4 is a view of the blank from which the rear portion of the lower member is formed,—the lower ends of the front blank, and which in the completed article form the coverings for the upper part of the feet, 50 showing in dotted lines;

Fig. 5 is a plan view of the blank that forms the sole of one of the feet.

Fig. 6 is a perspective view of one of the foot portions, showing also a portion of the 55 leg to which such foot portion is sewed; and

Fig. 7 is a plan view of one of the gus-

sets that connect the front and back pieces of the lower member of the garment.

In the several figures of the drawing—10 and 10^a represent the front and rear portions, respectively, that, when sewed together, form the body member of the garment. One of these portions is divided longitudinally as usual to enable the garment to be put on and removed from the infant, such division, in the construction shown, being in the center of the back portion, and the adjacent edges of this divided portion are provided as usual with a row of buttons and buttonholes, respectively. Near 15 the lower edge of both the front and back portions of the body member is secured a band 11 upon which are fastened a row of buttons to which the lower or trousers member of the garment is adapted to be secured. 20 This enables the two members to be separated entirely from each other, which is an advantage, of course, as sometimes it may only be necessary to wash one member. However, I do not wish to restrict myself to 25 this construction that permits the complete separation of the two members, for it will be apparent that a sufficient exposure of the child's diaper can be effected if the rear part of the lower or trousers member be continuous with or permanently attached to the 30 rear part of the body member. That this is so will be apparent in the light of the description of the operation later given herein, as well as from an inspection of Fig. 3. I 35 prefer the construction shown as, in addition to the advantage of separately laundering the two members as stated, it is sometimes an advantage to let down the upper part of the rear portion of the lower member; 40 as illustrated in Fig. 2.

12 and 12^a represent the front and rear portions, respectively, that, when sewed together, form the lower or trousers member of the garment. These two portions are 45 sewed together along their side margins except at their upper ends, and at their upper ends and at each side of the garment there is inserted between them a gusset 13 of, approximately, triangular shape. The marginal portions of the gussets that are sewed to the front and rear trousers portions are of such length as to extend downward to quite an extent, and as each gusset at its upper end is quite wide the effect is to permit 50 the turning down of quite a large flap of the material at the upper end of the trousers

member,—such flap being either at the front or rear, in the construction illustrated, accordingly as said member is unbuttoned at the front or rear. As clearly shown in Fig. 3, with the infant on its back and the front 5 of the trousers member of the garment unbuttoned a quite large opening is afforded sufficient to permit of the required changing of the diaper, which opening may be somewhat 10 further enlarged temporarily if deemed advisable by slightly turning back the lower end of the front portion 10 of the body member, as shown. It will be noticed that when the garment is opened up by the raising and 15 turning down of the flap formed by the upper part of the portion 12 the gussets are so drawn out as to form effective guards or shields at the sides of the opening and thus act to very effectively protect the infant's 20 body from drafts. Of course, the same shielding effect is secured if only the rear flap is let down, but the front flap is the one that will ordinarily be opened up as it is beneath that that the diaper fastenings are 25 ordinarily placed, and it is in the protection at that time of the abdomen from air currents that the shielding effect of the gussets is of greatest value. When the lower garment member is buttoned up in place each of the 30 gussets 13 will naturally fold over upon itself and in that condition it will very completely and effectually close the space from the point where the sewed-together margins of the portions 12—12^a end to substantially 35 the waist line. Thus each gusset in its folded-together condition acts to close what would otherwise be a long opening at the side that would be apt to admit cold air upon the infant's tender body.

40 Turning now to the other feature that characterizes my improved garment it will be noted that the front part of each of the leg sections of the portion 12 is longer than its companion rear part by a sufficient 45 amount of material to constitute the upper part of a foot covering, such upper part, designated by 12^b, having its outer end cut on a curve to approximate the toe of an ordinary foot covering. The rear part of each 50 of the leg sections of the portion 12^a is cut off on a straight line as clearly shown in Fig. 4, and to that straight marginal portion thus formed is sewed a corresponding straight marginal portion of a sole member. This 55 sole member is formed from a piece of cloth shaped as in Fig. 5, the straight end margin there shown being the margin that is above referred to as being sewed to one of the straight ends of a leg member 12^a. The sole

member, indicated generally by 14, is shaped 60 to conform to the shape of the upper foot part 12^b to which it is sewed along its edges. To give a semblance of foot-shape the part 14 is folded upon itself longitudinally and at its rear where so folded it is stitched together 65 as clearly shown in Fig. 6, which stitching holds the cloth sufficiently in shape to resemble and act as a foot covering somewhat after the style of a moccasin, and, it will be noted, leaving the under portion or sole 70 proper wholly seamless, where formed as shown and described. This part 14 in addition to constituting the sole proper also forms for the greater portion of its length the sides of the foot covering. 75

By my invention I provide a garment which will inclose an infant from its neck downward and protect all parts of its body and limbs from drafts or cold air, but which can be readily opened from time to time to 80 permit of making the required changes of diapers, and at such times will also act, in large measure, to protect it from drafts and cold air.

What I claim as my invention, and desire 85 to secure by Letters Patent is,—

1. A child's garment comprising in combination a body member and a trousers member, said two members being detachably connected together at both the front and rear 90 of the garment and said trousers member being divided along each of its sides for a limited distance downward from its upper edge whereby front and rear flaps are formed, either of which may be disconnected 95 from the body member and turned down without disturbing the connection of the other, and a foldable gusset at each side connecting together the marginal portions of the two flaps and closing the trousers member at that place but permitting the turning down of either flap. 110

2. A child's garment comprising in combination a body member and a trousers member, said trousers member comprising front 105 and rear pieces, the leg portions of said front piece being longer than the rear piece to form extensions to project over the feet of the wearer, and sole pieces each sewed to the margins of one of said extensions and also 110 to the lower margin of the rear and shorter portion of the leg piece, the rear of the said sole piece being folded upon itself and sewed together along such fold to approximately shape the sole piece to the foot of the 115 wearer.

ELsie May BLANK.
